Patented Sept. 13, 1960

188,800

HAY BALER

Constantine J. Kermes, Lancaster, and Edwin B. Nolt, James W. McDuffie, and Otto W. Luck, New Holland, Pa., assignors to Sperry Rand Corporation, New Holland, Pa., a corporation of Delaware

Filed Feb. 6, 1958, Ser. No. 49,528

Term of patent 14 years

(Cl. D40—1)

Fig. 1.

Fig. 2.

Fig. 3.

Fig. 1 is a front perspective view taken from the top and left side of a hay baler embodying our new design;

Fig. 2 is a front perspective view taken from the right side thereof on a reduced scale; and

Fig. 3 is a rear perspective view taken from the left side thereof on a reduced scale.

The tongue is shown broken away for convenience of illustration in Figs. 1 and 3.

The dominant features of our design reside in the full line portions of the drawing.

We claim:

The ornamental design for a hay baler, as shown and described.
